Application February 15, 1934, Serial No. 711,384
Renewed January 11, 1936

24 Claims. (Cl. 246—130)

Our invention relates to apparatus for the control of highway crossing signals, and particularly to apparatus for providing a uniform period of warning at the highway.

A feature of our invention is the provision of apparatus, governed by a train approaching a highway intersection, which operates to control the highway crossing signal in such a manner that substantially an equal time of operation of the highway crossing signal before the train reaches the intersection is obtained regardless of the speed, and which apparatus is effective to modify such control if the train is accelerating by starting the operation of the signal when the train reaches a fixed point. Another feature of our invention is the provision, in apparatus of the aforesaid type, of novel and improved means for providing for a measuring track section which is relatively short with respect to an operating track section. A further feature of our invention is the provision of apparatus of the type here involved which is operative at times to return to its normal position at a speed materially greater than the rate of speed at which it ordinarily returns to such position. Other features and advantages of our invention will appear as the specification progresses.

We will describe one form of apparatus embodying our invention, and will then point out the novel features thereof in claims.

In the accompanying drawings, Fig. 1 is a diagrammatic view of one form of apparatus for controlling the operation of a highway crossing signal which embodies our invention. Figs. 2 and 3 are views partly diagrammatic and partly in section of the portion of the apparatus of Fig. 1 which checks whether or not a train is accelerating. Fig. 4 is a plan view of the gear reduction assembly GR of Fig. 1, and Fig. 5 is a sectional view on the line V—V of Fig. 4.

In each of the different views like reference characters designate similar parts.

Referring to Fig. 1, the reference characters 1 and 1^a designate the traffic rails of a railway over which traffic normally moves in the direction indicated by the arrow and which rails are intersected at grade by a highway H shown at the right-hand end of the drawing. At the intersection there is located a highway crossing signal S. This signal S may take different forms, and is here shown conventionally as a combined audible and flashing light highway crossing signal. It will be understood, however, that our invention is not limited to this specific type of signal and any of the standard highway crossing signals may

be used. The signal S is normally inactive and is rendered active to display a warning to the highway users whenever a train approaches the intersection. The immediate control of the signal S is governed by a mechanism indicated by the reference character FR, which mechanism is effective to cause the signal S to exhibit a warning in response to current supplied thereto.

The traffic rails 1 and 1^a are divided by the usual insulated rail joints preferably into four track sections A—B, B—C, C—D and D—E, which track sections are traversed successively in the order named by a train approaching the highway. Each of these track sections is provided with a track circuit comprising a track battery 2 and a track relay designated by the reference character R with an exponent corresponding to its location. Interposed between the track relay R^A and the rail 1 of the section A—B is a front contact 3 of the track relay R^B. Interposed between the track relay R^B and the rail 1 of the section B—C is its own front contact 4, forming thereby a stick circuit for that relay over which it is normally energized. The relay R^B is further provided with a pickup circuit which includes a normally closed contact 55—56 of a time measuring device indicated as a whole by the reference character TM and to be described later, and a front contact 6 of the track relay R^C as will be understood by an inspection of Fig. 1. The function of this control for the two track relays R^A and R^B will become apparent as the description proceeds.

For the purpose of this specification we shall refer to the section A—B as a measuring section, the track sections B—C and C—D taken together as an operating section, and the track section D—E as a positive operating section. As will appear hereinafter, the speed of a train as it travels over the measuring section A—B is measured. Whether or not the train is accelerating is determined while the train travels the measuring section A—B and the track section B—C of the operating section. The highway crossing signal S is set into operation as the train travels the operating section in accordance with the measured speed and in accordance with whether or not it is accelerating. The time of starting the operation of the signal is such that substantially an equal interval of operation before the train reaches the highway H is assured regardless of the speed of the train as long as its speed remains approximately constant, while the operation of the signal S is started as soon as the train enters the section C—D if the train is accelerating. Positive operation of the signal S takes place dur-

ing the time a train occupies the track section D—E irrespective of whether or not it is moving.

That the ideas may be fixed and the operation of the apparatus of our invention more readily understood, we shall assume the maximum speed for all trains to be 90 miles per hour and that twenty seconds exhibit of the highway crossing signal before the train reaches the highway is desired. A train traveling 90 miles per hour will advance approximately 2640 feet in twenty seconds. The length of the operating section, in this instance, the combined lengths of the track sections B—C and C—D, is preferably something greater than 2640 feet, say for example 3200 feet, in order to compensate for the usual delay in the release of the track relays and the time necessary to energize the various controlling devices. The positive operative section is preferably made short, say only 200 feet. That is, the section D—E is preferably just long enough that operation of the signal S while a train is in the immediate vicinity of the highway H whether it is moving or not is assured. That a more accurate determination of the train speed may be obtained, the measuring section is preferably made shorter than the operating section, and for reasons to appear later, it is made in this instance one-fourth the length of the operating section, namely, 800 feet in length. For the purpose of checking the train speed for acceleration, the track section B—C immediately following the measuring section A—B is also made 800 feet in length. It will be understood, of course, that our invention is not limited to the above lengths for the several track sections, and their lengths will be arranged to suit each individual location and to suit different maximum speeds and different intervals of operation of the highway crossing signals.

The time measuring device TM comprises a speed measuring element, an acceleration checking element and a centrifugal governor. The speed measuring element includes a shaft shown schematically by a dotted line 7 and four circuit controlling contact disks 8, 9, 10 and 11, of suitable nonconducting material, rigidly mounted on the shaft 7. The shaft 7 is driven by a constant speed motor M through the medium of a suitable gear reduction designated by the reference character GR. The disks 8, 9, 10 and 11 normally occupy the position in which they are illustrated in the drawings, and are arranged to be at times rotated away from this normal position clockwise toward a reverse position by operating the motor M in one direction, the full reverse position being a little less than one revolution. At other times these disks are restored to the normal position by reversing the operation of the motor. The gear reduction GR may take different forms and preferably is that disclosed and claimed in the United States Letters Patent No. 1,991,756, granted February 19, 1935, to B. Lazich, for Apparatus for changing speed and direction of rotation by reversing a constant speed motor. As the specific structure of this gear reduction forms no part of our present invention, it is shown conventionally in Fig. 1 for the sake of simplicity, and it is deemed sufficient for this specification to point out that with the motor M rotated in the direction to drive the disks 8, 9, 10 and 11 clockwise, the shaft 7 will be driven at the speed of one revolution per minute. When the motor is reversed and the disks driven in the counter-clockwise direction, the rate of speed will be one-fourth revolution per minute. To put it

another way, these disks are rotated from the normal toward the reverse position at the rate of one revolution per minute and are rotated from the reverse position toward the normal position at the rate of one-fourth revolution per minute, the driving motor M operating at the same constant speed in both cases. The function of this change of speed for the speed measuring element will appear when the operation of the apparatus is described.

Figs. 4 and 5 disclose in detail the gear reduction GR of Fig. 1. The motor shaft 7^a of motor M rotates at a constant speed clockwise or counter-clockwise in accordance with the direction of operation of the motor armature 67. A ratchet 90 fits loosely on shaft 7^a and has rigidly fastened to its hub 91 a gear 92. A second ratchet 93 fits loosely on shaft 7^a and has rigidly fastened to its hub 94 a gear 95. A screw thread 106 is cut on the shaft 7^a and engages a ratchet nut RN causing it to move along the axis of shaft 7^a thereby engaging either the ratchet 90 or the ratchet 93 to drive either the gear 92 or the gear 95. The gears 92 and 95 engage gears 96 and 97, respectively, which are fastened to the operating shaft 7 by pins 98 and 99, respectively. A compression spring 100 is provided in back of gear 92 and is held in place by a cup 101 pinned to shaft 7^a by a pin 102. In like manner a compression spring 103 is provided in back of gear 95 and is held in place by a cup 104 pinned to shaft 7^a by a pin 105. Operation of motor M in the direction corresponding to that established in response to a train occupying the measuring section A—B, causes the ratchet nut RN to engage ratchet 93 and the shaft 7 is driven through gears 95 and 97, the rotation of shaft 7 being clockwise as viewed in Fig. 1 and relatively high. Operation of motor M in the direction corresponding to that established in response to a train in the operating section B—D, causes the ratchet nut RN to engage ratchet 90 and shaft 7 is driven through gears 92 and 96, the rotation of shaft 7 being counter-clockwise, as viewed in Fig. 1 and relatively low. The parts are so proportioned that shaft 7 is driven at one revolution per minute in response to a train in the measuring section and is driven at one-fourth revolution per minute in response to a train in the operating section.

The disks 8, 9, 10 and 11 are utilized for controlling the various circuits and to this end each is provided with a contact ring adapted to engage suitable stationary contact springs in the following manner. A contact ring 51 is mounted on the circumference of the disk 8 and is adapted to bridge the stationary contact springs 43 and 44 at all times except at the full reverse position when the ring 51 moves out from beneath the spring 44 to open the connection between springs 43 and 44. Mounted on the circumference of the disk 9 is a contact ring 52 which is adapted to bridge the stationary contact springs 53 and 54 at all times except at the full normal position. A contact ring 57 mounted on the disk 10 is adapted to bridge the stationary contact springs 55 and 56 in the full normal position only. A contact ring 60 mounted on the disk 11 is adapted to bridge the stationary contact springs 58 and 59 in the normal position and is so proportioned that the connection is broken between these two springs 58 and 59 when the disk 11 has been rotated clockwise approximately five seconds. Hence, the connection between the springs 58 and 59 will be again made approximately twenty sec-

onds before the full normal position of the disk 11 is reached during the reverse to normal movement, it being recalled that the rate of rotation in the reverse to normal movement (counter-clockwise) is only one-fourth the rate of rotation during the normal to reverse (clockwise) movement. The manner by which these several contact disks control the various circuits will also appear when the operation of the apparatus is described.

The acceleration checking element of the device TM comprises a shaft shown schematically by the dotted line 12 and two contact disks 13 and 14 mounted thereon. The shaft 12 is driven by the constant speed motor M through the medium of a suitable train of gears indicated by a pinion 15 and a gear wheel 16. The arrangement is such that with the motor M operated in the direction to drive the disks 8, 9, 10 and 11 of the speed measuring element in the clockwise direction, the shaft 12 is likewise rotated clockwise and at the speed of one revolution per minute. With the motor M reversed, the shaft 12 is rotated counter-clockwise at the same speed of one revolution per minute. Hence, the rate of rotation of the shaft 12 of the acceleration checking element is one revolution per minute during both the normal to reverse and the reverse to normal operation, whereas, the shaft 7 of the speed measuring element is rotated at one revolution per minute during the normal to reverse operation and is then rotated at one-fourth revolution per minute during the reverse to normal operation.

Referring now to Figs. 2 and 3 as well as to Fig. 1, the contact disk 13 is of non-conducting material and is pinned to the shaft 12 by a pin 17 and has mounted around its circumference a contact ring 18, with which a stationary contact spring 19 is adapted to make engagement. The disk 14 is preferably of non-conducting material like the disk 13 but is mounted loosely on the shaft 12. The disk 14 is provided with a contact ring 20, a stationary contact spring 21 being adapted to make engagement therewith. The contact ring 18 of the disk 13 is provided with a socket arrangement 22 extruding from the side of the disk 13 opposite the disk 14. The contact ring 20 of disk 14 is provided with a similar construction except in place of a socket, a pin 23 is provided which engages the socket 22 on the disk 13. It follows that at such time as the pin 23 engages the socket 22, electrical connection is completed between the rings 18 and 20, and hence between the two contact springs 19 and 21. Fastened to the disk 14 is a ratchet wheel 24. A ratchet pawl 25 pivotally mounted at 26 is provided which engages the ratchet wheel 24. The pressure of the ratchet pawl 25 against the ratchet wheel is adjusted by means of a compression spring 27 and a screw 28 which can be locked in position by a lock nut 29 after proper adjustment is made. The arrangement of the parts is such that when the shaft 12 is driven clockwise as viewed in Fig. 1 and counter-clockwise as viewed in Fig. 3, the contact disk 13 will rotate and move the socket 22 away from the pin 23 of disk 14, the ratchet pawl 25 preventing movement of the disk 14. Consequently, the disk 13 when rotated as stated above will be effective to open the electrical connection between the two springs 19 and 21. After the above initial operation of the disk 13 a reversal of the direction of rotation of the disk 13 will bring the socket 22 back into engagement

with the pin 23 and again restore electrical connection between the two springs 19 and 21. If it is so arranged that the disk 13 is driven in the clockwise direction as viewed in Fig. 1 at a given speed while a train is passing over a certain length of track section and is then reversed and driven in the opposite direction at said given speed while the train is travelling through a second track section of equal length, whether or not the train is accelerating will be determined. If the train is running at a constant speed, it will consume an equal period of time in travelling each of the two track sections and hence the socket 22 of the disk 13 will be back in engagement with the pin 23 as the train reaches the outgoing end of the second track section. If, however, the train is accelerating, it will travel the second track section in a shorter time than it required to pass over the first track section and the electrical connection between the socket 22 and the pin 23 will not be restored by the time the train reaches the outgoing end of the second track section. It is clear, therefore, that connection between the two springs 19 and 21 of the acceleration checking element of the device TM is normally closed and will be first opened and then subsequently closed in response to a train travelling at constant speed over the two aforementioned sections, and the electrical connection between these two springs will not have been closed if the train is accelerating. In the event there is deceleration of the train speed, the connection between the two springs 19 and 21 will have been closed prior to the time the train reaches the outgoing end of the second section. In this last case, the disk 13 is rotated clockwise, as viewed in Fig. 3, after the socket 22 has engaged the pin 23, and the disk 14 will be driven along with the disk 13 in the clockwise direction, the ratchet wheel 24 slipping over the ratchet pawl 25. It follows that the two disks 13 and 14 will always be in a condition for checking the acceleration of a train as it travels over the two previously mentioned track sections notwithstanding the point from which their operation will initially start may vary. The manner whereby this acceleration checking element cooperates with the speed measuring element in controlling the operation of the signal S will shortly appear.

A centrifugal governor N is operatively connected with the motor M as indicated in Fig. 1 by a dotted line 30, and this centrifugal governor controls a circuit controlling contact C1. The parts are so proportioned and adjusted that the contact C1 rests in engagement with two contacts 31 and 32 as long as the motor is at rest and is lifted out of engagement therewith whenever the motor is rotated at a predetermined rate of speed. Rotation of the motor M in either direction at a rate above a predetermined value will cause the contact C1 to be lifted high enough to make engagement with two contacts 33 and 34. It follows that the operating condition of the motor M is checked by the position of the contact C1.

Two relays SR and TP are provided and serve as the medium for controlling the supply of current to the signal operating mechanism FR, the relay SR being of the usual neutral type and the relay TP being slow releasing in character. The relay SR is provided with an energizing circuit extending from the X terminal of any convenient source of current such as a battery not shown over front contact 39 of the track relay R^A, wire 40, front contact 41 of the track relay R^C, wind-

ing of the relay SR and thence over a front contact 42 of the track relay R^D to the opposite Y terminal of the current source. The relay SR is further provided with a stick circuit network comprising four separate paths over any one of which the relay may be retained energized. A first path includes the X terminal of the current source, contact 43—44 of the disk 8, wire 45, front contact 46 of the relay SR, front contact 41, winding of relay SR and thence to the Y terminal of the current source over the front contact 42 of the track relay R^D. A second path can be traced from the X terminal of the current source over a back contact 47 of the relay 15 TP to the wire 45 and thence as traced for the first path. A third path is traced from the X battery terminal over the contact 43—44, wire 45, front contact 46, wire 48, contact springs 19 and 21 of the acceleration checking element 20 with the contact 22—23 closed, wire 49, winding of the relay SR and to the Y battery terminal over the front contact 42 of track relay R^D. A fourth path extends from the X battery terminal over the back contact 47 of the relay TP to the 25 wire 45 and thence over the same path just traced for the third path. The relay TP is energized over a simple circuit easily traced and which includes a front contact 50 by the track relay R^B and hence this relay TP serves as a repeater 30 relay for the track relay R^B.

Referring to the drawings, the operation of our system can be explained in the following manner. As long as no train occupies any of the track sections, the track relays R^A, R^B, R^C and R^D 35 are all picked up, relays SR and TP are energized, motor M is without current, the time measuring device TM occupies the position illustrated in Fig. 1 and the signal S is inactive. When a train approaching the highway H from the left 40 enters the track section A—B, the track relay R^A will be shunted and that relay will be released. As relay R^A is released, current will be supplied to the motor M, and it will be operated to drive the operating shafts 7 and 12 in the clockwise 45 direction. To be explicit, the motor M will be supplied with current from the X terminal of the current source over contact 43—44, field winding 61, wire 72, front contact 62 of the relay SR, back contact 63 of the relay R^A, front contact 64 of the relay R^B, wire 73, a front pole-changing contact 65 of the relay R^B, a back pole-changing contact 66 of the relay R^A, motor armature 67, a resistor 37, a second back pole-changing contact 68 of relay R^A and a second front pole-changing 50 contact 69 of the relay R^B to the Y terminal of the current source. The energization of the motor M by this circuit just traced is such as to cause it to rotate in the direction for driving the operating shafts 7 and 12 in the clockwise direction. 55 The parts are so proportioned that the speed of the motor M will be substantially constant at a given value such that the rate of rotation of one revolution per minute for the shafts 7 and 12 will be obtained. This speed of the motor M will be of such value that the contact C1 of the centrifugal governor N will be lifted out of engagement with the contacts 31 and 32 but will not be raised high enough to engage the contacts 33 and 34. As soon as the disk 9 is rotated clockwise 60 away from the normal position, the contact 53—54 will be closed and a path between the wires 72 and 73 will be completed which short circuits the path in the motor circuit including the front contact 62 of the relay SR, the back contact 63 of the relay R^A and the front contact 64 of the

relay R^B. After a slight movement of the disk 10, the connection between the springs 55 and 56 will be opened, and after approximately five seconds operation of the shaft 7 in this normal to reverse movement, the connection between the springs 58 and 59 of disk 11 will be opened. Rotation of the shaft 12 of the acceleration checking element in the clockwise direction causes the socket 22 on the disk 13 to move out of engagement with the pin 23 and hence the connection 10 between the two springs 19 and 21 will be broken. This operation of the last three mentioned contacts, however, performs no useful function at this time and their purpose will appear later. It follows that as the train advances through the 15 measuring section A—B, the speed measuring element and the acceleration checking element of the time measuring device will be operated in the clockwise direction at the speed of one revolution per minute. It will be noted that should the train 20 stop in the section A—B, the circuit for the motor M will eventually be opened at the contact 43—44 when the full reverse position is reached, which position, as stated hereinbefore, is something less than one revolution, and the operation 25 will be stopped. The shunting of the track relay R^A as the train enters the section A—B opens at the front contact 39 the energizing circuit for the stick relay SR, but that relay will now receive current over its stick circuit which includes the 30 contact 43—44, its own front contact 46, and the front contact 41 of the relay R^C, and it will be held energized, since this stick circuit is closed previous to the shunting of the track relay R^A. In the event the speed measuring element is operated to its full reverse position, the above stick circuit will be opened at the contact 43—44 and the relay SR will be deenergized. 35

Assuming that the train advances through the measuring section A—B without stopping and 40 enters the track section B—C, the track relay R^B will be shunted and that relay will be released. The opening of the front contact 3 of the relay R^B causes the track relay R^A to be without current and to remain deenergized until such time 45 as the track relay R^B will again be picked up. With the relay R^A held down, the previously traced circuit for the motor M will remain closed at the back pole-changing contacts 66 and 68 of that relay the same as when the train occupied 50 the section A—B. The track relay R^B upon releasing will open the front pole-changing contacts 65 and 69 and close corresponding back pole-changing contacts 70 and 71 with the result that the direction of the flow of current 55 through the armature 67 of the motor M will be reversed while the direction of the flow of current through the field winding 61 will remain the same. This reversal of the direction of current flow in the armature 67 reverses the rotation of the motor, and the operating shafts 7 and 12 will now be driven in the counter-clockwise direction from the point to which they had advanced while the train was passing through the measuring section A—B. Due to the gear reduction GR, the rate of rotation of the shaft 7 will be only one-fourth of a revolution per minute, but as the gear train 15—16 remains the same the rate of rotation of the shaft 12 will still be one revolution per minute. The release of the 60 track relay R^B will also open the circuit to the relay TP and that relay will be released at the end of its slow-release period. The release of the repeater relay TP completes an operating circuit which makes possible the supplying of 65

current to the mechanism FR to start operation of the signal S. This operating circuit includes two parallel paths one of which extends from the X terminal of the current source over a back contact 74 of the relay TP, wire 75, contact 58-59 of the disk 11 when bridged by the contact ring 60, wire 76, and the mechanism FR to the opposite Y terminal of the current source. In parallel with the contact 58-59 is the second path extending from the wire 75 through contact C1 of the centrifugal governor N in engagement with either contacts 31 and 32 or in engagement with the contacts 33 and 34 to the wire 76 and thence as before traced. Should the motor M fail to operate in the reverse direction in response to a train entering the section B-C, or operate at a speed above its proper speed, the releasing of the relay TP will be effective to supply current to the mechanism FR over contact C1 and the signal S will be set into operation at once, with the result that operation of motor M is checked. The repeater relay TP being slow releasing in character, the above traced operating circuit will not be closed at the back contact 74 of that relay until after the instant the contact C1 of the centrifugal governor makes engagement with the contacts 31 and 32 as the motor is being reversed, and hence a flash of the signal S as the motor M reverses will be avoided.

As stated hereinbefore, the parts are so proportioned that the connection between the springs 58 and 59 will not be opened until the speed measuring element has been driven away from the normal position for approximately five seconds. A train travelling at the maximum speed of 90 miles per hour will consume only a fraction over five seconds in passing through the measuring section A-B, and hence it will enter the section B-C and cause a reversal of the operation of the speed measuring element approximately at the same interval that the contact 58-59 will be opened. Under this condition, this contact 58-59 will be closed by the time the relay TP is released and current will be supplied to the mechanism FR to start operation of the signal S with the result that operation of the signal S during the entire time the train is travelling the operating section will be obtained and the desired twenty seconds operation of the signal before the train reaches the highway will be provided. In the event a train passes over the measuring section at a speed less than the maximum speed, say, for example, 60 miles per hour, it will consume approximately nine seconds before it reaches the exit end of the track section A-B and its head end enters the section B-C with the result that the contact 58-59 will have been opened approximately the last four seconds of this nine second period. In this case the contact 58-59 will not be closed until the disk 11 has been operated counter-clockwise for approximately sixteen seconds. A train travelling 60 miles per hour will consume about thirty-six seconds in passing over the operating section, and as there will be a delay of sixteen seconds in starting the operation of signal S a twenty seconds operation of the signal S before this train reaches the highway H will be provided. An analysis of the operation of the apparatus for trains travelling at other speeds less than the maximum will disclose that approximately twenty seconds operation of the signal S before the train reaches the highway will be obtained in each case.

After the repeater relay TP is released, the

stick relay SR will receive current over the stick circuit which includes the back contact 47 of the relay TP and the front contact 41 of the track relay R^C. It follows that the stick relay SR will be retained energized while the train passes over 5 the track section B-C.

It will be recalled that the track section B-C is made of the same length as the track section A-B, and hence for all trains advancing through these two track sections at substantially a constant speed the contact 22-23 of the acceleration checking element will be reclosed as the train reaches the outgoing end of the track section B-C and its head end enters the track section C-D. Under these circumstances relay SR will 10 receive current over the stick circuit including the back contact 41, front contact 46 and the contact 22-23 even after the track relay R^C has been shunted. Consequently, for all trains having substantially a constant speed the relay SR 15 will be retained energized while a train is in the operating section and the operating circuit for supplying current to the mechanism FR which includes the contact 58-59 of the speed measuring element or the contact C1 of the centrifugal 20 governor will be effective. It is clear, therefore, that with the motor M operating at the proper rate, the contact 58-59 of the speed measuring element will control the starting of the operation of the signal S in such a manner that substantially twenty seconds operation of the signal S 25 before the train reaches the highway will be obtained regardless of the speed of the train, if there is no acceleration.

We shall now consider the case where the train 35 is accelerating as it travels over the measuring section in approaching the highway H. Under this condition, the train will require less time to travel over the track section B-C than it consumed in passing over the track section A-B, 40 and, consequently, the contact 22-23 of the acceleration checking element will still be open as the head end of the train enters the track section C-D and shunts the track relay R^C. The stick relay SR will now be without an energizing 45 circuit and will be deenergized. Another operating circuit for supplying current to the mechanism FR will now be completed from the X battery terminal over a back contact 77 of the relay R^B, a back contact 78 of the stick relay SR, mechanism FR, and to the Y battery terminal. It follows, therefore, when a train is accelerating 50 as it moves over the measuring section, the acceleration checking element of the time measuring device is effective to prevent the delay in starting the operation of the highway crossing signal S which would be effected by the speed measuring element if the train moved through the measuring section at a constant speed, the operation of the signal being started through the medium of 55 the auxiliary operating circuit including the back contact 78 of the stick relay SR as soon as the train enters the track section C-D.

It is to be noted that the front contact 6 of 60 the track relay R^C prevents the track relay R^B from becoming energized while the train occupies the section C-D and in turn prevents the track relay R^A from picking up. Consequently, the stick relay SR once deenergized in the manner described above to start operation of the signal S, that relay will remain down until the train has moved out of section C-D. It will also be noted that the contact 55-56 of the disk 10, which contact is interposed in the pickup circuit 65 of the track relay R^B, prevents that relay from 70 75

becoming reenergized until the time measuring device TM is restored to its full normal position. When the train advances and occupies the track section D—E, the mechanism FR will receive current over another operating circuit which includes a back contact 79 of the track relay R^D, and thus operation of the signal S as long as the train occupies the section D—E, whether the train is moving or not, is assured.

In the event a train advances into the measuring section A—B from the left and then stops, the device TM will be operated to its full reverse position, as pointed out hereinbefore. Should the train now back toward the left out of the section A—B, both track relays R^A and R^B will be picked up and the motor M will be supplied with current from the X terminal of the current source over the front contact 39 of the relay R^A, wire 40, front contact 46 of relay SR, wire 45, field winding 61, wire 72, contact 53—54, wire 73, front pole-changing contact 65 of relay R^B, a front pole-changing contact 80 of relay R^A, a second front contact 81 of relay R^A, motor armature 67, a front pole-changing contact 82 of relay R^A and front pole-changing contact 69 of relay R^B to the Y terminal of the current source. The energization of the motor M by this circuit is that which causes the motor M to be operated in a direction to rotate the shaft 7 counterclockwise. As soon as the disk 8 is rotated away from the full reverse position, the contact 43—44 is closed and from this point on the motor M will receive current through that contact until the full normal position is reached when the motor circuit will be opened at the contact 53—54. During this operation of the motor, the front contact 81 of the track relay R^A short circuits the resistor 37 with the result that the motor M will be operated at a very much higher rate of speed, and the time measuring device will be restored to its normal position at a speed materially faster than its normal rate. Although the contact 33—34 of the centrifugal governor may be closed due to this increased rate of operation of the motor M, no operation of the signal S will occur inasmuch as the repeater relay TP is now energized.

In the event a train is travelling in the reverse direction, that is, against the normal direction of traffic, and enters the track section D—E from the right, the time measuring device TM will remain inactive. Under this condition, the track relay R^D is first deenergized to open the front contact 42 in the energizing circuit of the stick relay SR and that relay is deenergized. The front contact 62 of the stick relay SR being now open, the motor circuit is not completed as the track relays R^C, R^B and R^A are shunted, and hence the device TM is not operated away from its normal position while a train travelling in the reverse direction occupies the successive track sections.

It will be further noted that in the event a train is accelerating and the stick relay SR is deenergized as the train enters the track section C—D in the manner previously described, the closing of the back contact 83 of the relay SR short circuits the resistor 37 in the motor circuit and the motor is operated at the increased rate of speed to return the time measuring device TM quickly to its normal position.

Although we have herein shown and described only one form of apparatus embodying our invention, it is understood that various changes and modifications may be made therein within the

scope of the appended claims without departing from the spirit and scope of our invention.

Having thus described our invention, what we claim is:

1. In combination, a stretch of railway track intersected by a highway, a highway crossing signal located at the intersection, a member, means governed by a train in travelling a first fixed distance in approaching the intersection for driving said member in one direction at a given speed, means governed by the train in travelling a second and equal fixed distance in approaching the intersection for driving said member in the opposite direction at said given speed, operating means controlled by the train for setting the signal into operation when the train reaches a fixed point, and means controlled by said member operative when said member is driven in said opposite direction a distance at least equal to the distance said member is driven in said one direction to render said operating means ineffective.

2. In combination, a stretch of railway track intersected by a highway, a highway crossing signal located at the intersection, a motor operated speed measuring device set into operation when a train approaches the intersection for starting the operation of said signal at substantially the same interval of time before the train reaches the intersection regardless of the speed of the train, a member, means governed by a train in travelling a first fixed distance in approaching the intersection for driving said member in one direction at a given speed, means governed by the train in travelling a second and equal fixed distance for driving said member in the opposite direction at said given speed, and means controlled by said member operative when said member is driven a less distance in the opposite direction than in said one direction to cancel the control of said device.

3. In combination, a stretch of railway track intersected by a highway, a highway crossing signal located at the intersection, a motor operated speed measuring device set into operation when a train approaches the intersection for starting the operation of said signal at substantially the same interval of time before the train reaches the intersection regardless of the speed of the train, another operating means controlled by a train for setting the signal into operation when the train reaches a fixed point, a member, means governed by the train in travelling a first fixed distance in approaching the intersection for driving said member in one direction at a given speed, means governed by the train in travelling a second and equal fixed distance for driving said member in the opposite direction at said given speed, and means controlled by said member operative when said member is driven approximately an equal distance in both directions to render said other operating means ineffective.

4. In combination, a stretch of railway track intersected by a highway, a highway crossing signal located at the intersection, a motor operated speed measuring device set into operation when a train approaches the intersection for starting the operation of said signal at substantially the same interval of time before the train reaches the intersection regardless of the speed of the train, a motor operated time checking device set into operation when a train approaches the intersection for comparing the time consumed by the train in travelling over two successive fixed

distances of equal lengths, and means controlled by said checking device operative when the time consumed by said train in travelling the second fixed distance is less than that consumed by the train in travelling the first fixed distance to annul the control of said speed measuring device.

5. In combination, a stretch of railway track intersected by a highway, a highway crossing signal located at the intersection, a motor operated speed measuring device set into operation when a train approaches the intersection for starting the operation of said signal at substantially the same interval of time before the train reaches the intersection regardless of the speed of 10 the train, another operating means controlled by a train for setting the signal into operation when the train reaches a fixed point, a motor operated time checking device set into operation when a train approaches the intersection for comparing 15 the time consumed by the train in travelling over two successive fixed distances of equal lengths, and means controlled by said checking device operative when the time consumed by said train in travelling the distances is approximately equal 20 to render said other operating means ineffective.

6. In combination, a stretch of railway track, a signal located along the stretch, two successive track sections of approximately equal lengths, an operating circuit controlled by a train for 25 governing said signal, an acceleration checking device controlled by a train set into operation when a train enters the first of said sections for comparing the time consumed by the train in travelling over said two track sections, and means 30 controlled by said checking device operative when the time consumed in the two sections is approximately equal to render said operating circuit ineffective.

7. In combination, a stretch of railway track, 40 a signal located along the stretch, two successive track sections of approximately equal lengths, two operating circuits for controlling said signal and both normally inactive, a time measuring device controlled by a train set into operation 45 when a train enters the first of said sections for measuring the time consumed by the train in travelling over each of said two track sections, means controlled by said device operative to render one of said operating circuits active in accordance with the time consumed in travelling the first of said sections, and means controlled 50 by said device operative when the time consumed by said train in travelling the second of said sections is less than that consumed by the train in travelling the first of said sections to render the other of said circuits active.

8. In combination, a stretch of railway track intersected by a highway, a highway crossing signal located at the intersection; a first, a second 60 and a third track section over which a train successively passes in approaching said highway, said first and second track sections being of approximately equal lengths; a track circuit for each section including a track relay, one operating means for operating said signal by deenergizing the track relay of the second section, another operating means for operating the signal by deenergizing the track relay of the third section, a speed measuring device set into operation 65 by deenergizing the track relay of the first section for delaying said one operating means in starting operation of the signal according to the speed of the train, a member, means for driving the member in one direction at a given speed operative 70 upon the deenergizing of the relay of the first

section, means for driving the member in the opposite direction at said given speed operative upon the deenergizing of the relay of the second section, and means controlled by said member for governing said other operating means according 5 to the distances said member is driven.

9. In combination, a stretch of railway track intersected by a highway, a highway crossing signal located at the intersection, operating means for setting the signal into operation when a train 10 approaching the intersection reaches a fixed point, a first device controlled by the train to register the speed of the train as it approaches said fixed point and effective to delay the operating means in setting the signal into operation 15 for a period determined by the registered speed, a second device governed by the train as it travels a given distance in approaching the fixed point and an equal distance as it recedes from said point to determine whether or not the train is 20 accelerating, and means governed by the second device effective to cancel the control of the first device if acceleration is registered.

10. In combination, a stretch of railway track intersected by a highway, a highway crossing signal located at the intersection, a first and a second track section over which a train successively passes in approaching the highway and each of which is provided with a track relay, a time measuring device comprising a member normally 30 occupying one position and an electric motor arranged to move said member away from said one position in response to rotation of said motor in one direction and to restore said member to said one position in response to rotation of said motor 35 in the opposite direction, a first circuit means including a back contact of the track relay of said first section effective for energizing said motor in such manner that said motor is rotated in said one direction at a given constant speed, a second 40 circuit means including a back contact of the track relay of the second section effective for energizing the motor in such manner that said motor is rotated in said opposite direction at said given constant speed, a first operating means 45 controlled by said member and responsive to its position away from said one position for determining the time of starting operation of said signal, a stick relay controlled jointly by the track relays of said sections and a contact responsive 50 to the time said motor is rotated in the two directions respectively, and a second operating means for starting operation of said signal including a back contact of said stick relay.

11. In combination, a stretch of railway track intersected by a highway, a highway crossing signal located at the intersection, a time measuring device comprising a member normally occupying one position and an electric motor arranged to move said member away from said one position in response to rotation of said motor in one direction and to restore said member to said one position in response to rotation of said motor in the opposite direction, a first circuit means effective when a train approaching said highway passes a first fixed point for energizing said motor in such manner that said motor is rotated in said one direction at a given constant speed, a second circuit means including a resistor effective when the train passes a second fixed point 60 for energizing the motor in such manner that said motor is rotated in said opposite direction at said given constant speed, means controlled by said member and responsive to its position away from said one position for determining the time 65

70

75

- of starting operation of said signal, and traffic controlled means effective at times to short-circuit said resistor for causing said motor to rotate in said opposite direction at a speed higher than 5 said given constant speed for causing a quick return of the member to said one position.
12. In combination, a stretch of railway track intersected by a highway, a highway crossing signal located at the intersection, a first and a 10 second track section over which a train successively passes in approaching the highway and each of which is provided with a track relay, a time measuring device comprising a member normally occupying one position and an electric 15 motor arranged to move said member away from said one position in response to rotation of said motor in one direction and to restore said member to said one position in response to rotation of said motor in the opposite direction, a first 20 circuit means including a back contact of the track relay of said first section and a resistor effective for energizing said motor in such manner that said motor is rotated in said one direction at a given constant speed, a second circuit 25 means including a back contact of the track relay of the second section and said resistor effective for energizing the motor in such manner that said motor is rotated in said opposite direction at said given constant speed, means controlled 30 by said member and responsive to its position away from said one position for determining the time of starting operation of said signal, and a third circuit means effective at times for energizing the motor in such manner that said 35 motor is rotated in said opposite direction and including a front contact of the track relay of the first section for short-circuiting said resistor whereby said motor is rotated at a speed higher than said given constant speed and the member 40 quickly returned to said one position.
13. In combination, a stretch of railway track intersected by a highway, a highway crossing signal located at the intersection, a first and a second track section over which a train successively 45 passes in approaching the highway and each of which is provided with a track relay, a time measuring device comprising a member normally occupying one position and an electric motor arranged to move said member away from 50 said one position in response to rotation of said motor in one direction and to restore said member to said one position in response to rotation of said motor in the opposite direction, a first circuit means including a back contact of the track 55 relay of said first section and a resistor effective for energizing said motor in such manner that said motor is rotated in said one direction at a given constant speed, a second circuit means including a back contact of the track relay of the 60 second section and said resistor effective for energizing the motor in such manner that said motor is rotated in said opposite direction at said given constant speed, a first operating means controlled by said member and responsive to its position away from said one position for determining the time of starting operation of said signal, a stick relay controlled jointly by a train approaching the intersection and a contact responsive to the time said motor is rotated in the two 65 directions, a second operating means for starting operation of said signal including a back contact of the stick relay, and a third circuit means effective at times for energizing the motor in such manner that said motor is rotated in said opposite direction and including a back contact of the 70

stick relay for short-circuiting said resistor whereby said motor is rotated at a speed higher than said given constant speed and the member quickly returned to said one position.

14. In combination, a stretch of railway track intersected by a highway, a highway crossing signal located at the intersection, a first and a second track section over which a train successively passes in approaching the highway, a track relay for each section responsive to traffic conditions of the section, a time measuring device comprising a member normally occupying one position and an electric motor arranged to at times move said member away from said one position and at other times to restore said member to said one position, a first circuit including a back contact of the track relay of said first section effective for energizing said motor in such manner as to move the member away from said one position, a second circuit including a back contact of the track relay of the second section effective for energizing said motor in such manner as to restore the member to said one position, operating means governed by the track relay of the second section when deenergized effective to set the signal into operation, means controlled by said member responsive to its position away from said one position for determining the time of starting operation of said signal, and circuit means for energizing the track relay of the second section when the train vacates said second section including a contact controlled by said member and closed when and only when said member occupies said one position.

15. In combination, a stretch of railway track intersected by a highway, a highway crossing signal located at the intersection, two track sections of approximately equal lengths which a train successively travels in approaching the intersection, two operating circuits for setting said signal into operation, a first and a second member, means set into operation when a train enters the first of said sections for driving said members in one direction while the train is passing over said first section, means set into operation when a train enters the second section for driving said members in the opposite direction while the train is passing over the second section, means controlled by said first member operative to control one of said circuits in accordance with the distance said first member is driven in said one direction, and means controlled by said second member operative to control the other of said circuits in accordance with the difference between the distance said second member is driven in said one direction and the distance the member is driven in said opposite direction.

16. In combination, a stretch of railway track intersected by a highway and formed into a relatively short measuring section and a relatively long operating section on one side of the highway, a highway crossing signal located at the intersection, a slow acting device, means governed by a train occupying the measuring section for operating said device and including a first gear reduction, means governed by a train occupying the operating section for operating said device and including a second gear reduction, said first and second gear reductions having a ratio with respect to each other which is inversely the same ratio as the length of the measuring section to the length of the operating section, and operating circuit means governed by said slow acting device for setting said signal into operation.

17. In combination, a stretch of railway track intersected by a highway and formed with an operating section on one side of the highway having a length which requires a predetermined interval for a train moving at a given maximum speed to travel therethrough, a measuring section located adjacent the operating section remote from the highway and arranged relatively short in length, a highway crossing signal located adjacent the intersection, a slow acting device, motor operating means for actuating said device and including a first and a second gear reduction, said first and second gear reductions having a gear ratio with respect to each other which is inversely the same ratio as the length of the measuring section to the length of the operating section, a first circuit governed by a train occupying the measuring section for causing said motor to actuate said device through the first gear reduction, a second circuit governed by a train occupying the operating section for causing said motor to actuate said device through the second gear reduction, and an operating circuit controlled by said device for setting the signal into operation substantially the same interval before the train reaches the highway regardless of the speed of the train.

18. In combination, a stretch of railway track intersected by a highway and formed into a measuring section and an operating section on one side of the highway, said measuring section arranged relatively short in length compared with the length of the operating section, a highway crossing signal located at the intersection, a time measuring device including a member having a normal position and adapted to be moved away from its normal position toward a reverse position and to be moved back toward the normal position, means governed by a train when occupying the measuring section to operate said device for moving said member away from the normal position and including a first gear reduction, means governed by a train when occupying the operating section to operate said device for moving said member back toward the normal position and including a second gear reduction, said first and second gear reductions having a gear ratio with respect to each other which is inversely the same ratio as the length of the measuring section to the length of the operating section, and operating means governed by said member for setting said signal into operation.

19. In combination, a stretch of railway track formed into a measuring section and an operating section, said measuring section being relatively short with respect to the operating section, a constant speed motor, control means for operating said motor in one direction in response to a train traveling the measuring section and to operate the motor in the reverse direction in response to a train traveling the operating section, a shaft capable of being reversibly rotated, a first gear train having a relatively high gear ratio, a second gear train having a relatively low gear ratio, means effective to rotate the shaft in one direction through said first gear train when the motor is operated in its said one direction and effective to rotate the shaft in the reverse direction through said second gear train when the motor is operated in its said reverse direction whereby the shaft is rotated in one direction at a relatively high speed when a train occupies the measuring section and is rotated in the reverse direction at a relatively low speed

when a train occupies the operating section, and time measuring means operatively connected with the shaft and including a circuit controlling contact.

20. In combination, a stretch of railway track formed into a measuring section and an operating section, said measuring section being relatively short with respect to the operating section, a constant speed motor, control means for operating said motor in one direction in response to a train traveling the measuring section and to operate the motor in the reverse direction in response to a train traveling the operating section, a shaft capable of being reversibly rotated, a first gear train connected with the shaft and having a relatively high gear ratio, a second gear train connected with the shaft and having a relatively low gear ratio, coupling means governed by the direction of rotation of said motor and effective to drive said first gear train when the motor is operated in its said one direction and to drive said second gear train when the motor is operated in said reverse direction whereby the shaft is rotated in one direction at a relatively high speed when a train occupies the measuring section and is rotated in the reverse direction at a relatively low speed when a train occupies the operating section, and time measuring means operatively connected with the shaft and including a circuit controlling contact.

21. In combination, a stretch of railway track intersected by a highway and formed into a measuring section and an operating section on one side of the highway, said measuring section being relatively short with respect to the operating section, a highway crossing signal located at the intersection, a constant speed motor, control means for operating said motor in one direction in response to a train traveling the measuring section and to operate the motor in the reverse direction in response to a train traveling the operating section, a shaft capable of being reversibly rotated, a first gear train connected with the shaft and having a relatively high gear ratio, a second gear train connected with the shaft and having a relatively low gear ratio, coupling means governed by the direction of rotation of said motor and effective to drive said first gear train when the motor is operated in its said one direction and to drive said second gear train when the motor is operated in its said reverse direction whereby the shaft is rotated in one direction at a relatively high speed when a train occupies the measuring section and is rotated in the reverse direction at a relatively low speed when a train occupies the operating section, and time measuring means operatively connected with the shaft and including a circuit controlling contact.

22. In combination, a stretch of railway track intersected by a highway and formed into a measuring section and an operating section on one side of the highway, said measuring section being relatively short with respect to the operating section, a highway crossing signal located at the intersection, a constant speed motor, control means for operating said motor in one direction in response to a train traveling the measuring section and to operate the motor in the reverse direction in response to a train traveling the operating section, a shaft capable of being reversibly rotated, a first gear train connected with the shaft and having a relatively high gear ratio, a second gear train connected with the shaft and having a relatively low gear ratio, cou-

- pling means effective to drive said first gear train when the motor is operated in its said one direction in response to a train occupying the measuring section and to drive said second gear train when the motor is operated in its said reverse direction in response to a train occupying the operating section, and time measuring means including a circuit controlling contact operatively connected with the shaft for governing the operation of said signal.
23. In combination, a stretch of railway track intersected by a highway and formed into a measuring section and an operating section on one side of the highway, a highway crossing signal located at the intersection, a shaft having mounted thereon a circuit controlling contact which is adapted to be set at a given normal position, a first and a second gear train, a motor, means controlled by a train occupying the measuring track section to operate the motor in one direction to drive the shaft through the first gear train for moving said contact away from its normal position, other means controlled by a train occupying the operating track section to operate the motor in the other direction to drive the shaft through the second gear train for moving said contact toward its normal position, and circuit means controlled by said contact for governing said signal.

24. In combination, a stretch of railway track intersected by a highway and formed into a measuring section and an operating section on one side of the highway, a highway crossing signal located at the intersection, a constant speed motor having a given speed, control means for operating said motor in one direction in response to a train occupying the measuring section and in the opposite direction in response to a train occupying the operating section, a shaft, a first gear train connected to said shaft and capable when driven at said given speed of rotating said shaft at a relatively high speed, a second gear train connected to said shaft and capable when driven at said given speed of rotating said shaft at a relatively low speed, coupling means governed by the direction of rotation of said motor for selectively driving said first or said second gear train whereby said shaft is rotated in one direction at a relatively high speed when a train is traveling the measuring section and is rotated in the opposite direction at relatively low speed when a train is traveling the operating section, and a circuit controlling contact operatively connected with said shaft for governing said signal.
